UNITED STATES PATENT OFFICE.

JOHN C. KELTON, OF SAN FRANCISCO, CALIFORNIA.

MAGAZINE-GUN.

SPECIFICATION forming part of Letters Patent No. 313,213, dated March 3, 1885.

Application filed June 23, 1884. (No model.)

To all whom it may concern:

Be it known that I, JOHN C. KELTON, of the city and county of San Francisco and State of California, have invented an Improvement in 5 Breech-Loading and Magazine Fire-Arms; and I hereby declare the following to be a full, clear, and exact description thereof.

My invention relates to certain improvements in breech-loading and magazine fire-10 arms; and it consists of a gun having a hinged swinging breech-block with a hinge at the upper front portion, so that the block is thrown upward and forward when the breech is opened, and, in connection therewith, of a tubular firing-pin contained within the breech-block, a spring within said firing-pin, by which it may be forced forward, so that its point will strike and explode the cartridge within the barrel, a means for withdrawing this firing-pin, and 15 at the same time compressing the spring when the breech-block is thrown open, a sear and mechanism for holding the pin after the breech-block is closed, and a mechanism connected with the trigger, so that the spring may be 20 released to act upon the firing-pin by pulling the trigger.

My invention further consists in the application of a magazine in the form of a segment of a cylinder extending around beneath the 30 breech-block chamber, and having a hinged door opposite one side of the chamber, through which the cartridges may be dropped into the chamber when the breech-block is open.

Referring to the accompanying drawings 35 for a more complete explanation of my invention, Figure 1 is a front view of the sear. Fig. 2 is a side view of the sear. Fig. 3 is a bottom view of the sear. Fig. 4 is a rear view of the tubular firing-pin and transverse bar. Fig. 5 is a side view of the pin. Fig. 6 is a 40 top view of the same. Fig. 7 is a longitudinal vertical section of the breech movement closed. Fig. 8 is a side view of the breech movement open. Fig. 9, Sheet 2, is a perspective view showing the rifle with the breech-block opened and the magazine in place.

A is a receiver at the rear of the barrel of the gun, within which the breech-block B works. This breech-block is hinged at the 50 top of its front end to the rear portion of the barrel, so that it may be thrown upward and forward when opened, and when closed it lies

within the receiver and is held by a cam-latch, h', a thumb-piece, h, projecting to one side, and connected with the same shaft as the cam-latch, so that the breech-block may be thrown open by pressing upward upon the thumb-piece, in the manner of the present Springfield rifle.

In my invention I have shown a projection 60 or lug, H, beneath which the edge of the thumb-piece may be pressed by a slight movement after the breech-block is closed, and insure it from being thrown open by the explosion of the cartridge. The breech-block B is 65 made hollow, and within it is a hollow cylindrical firing-pin, C, having a projecting point, C, which may extend through a corresponding hole in the front end of the breech-block, so as to strike against the cartridge or primer 70 and explode it when the firing-pin is projected forward by the action of the spring. The mainspring D is contained within the hollow firing-pin C, its front end pressing against the front interior of the firing-pin, 75 while its rear end presses against the inclined sloping shoulder E' of the sear E. This sear E is pivoted below its center upon the pivot-screw e'', which is fixed from side to side of the breech-block, passing through the slot C' 80 in the rear portion of the firing-pin, as shown, this method of pivoting, together with the action of the rear end of the mainspring against the sloping shoulder E', causing the necessary movement to engage the sear-nosing e with 85 the notches c c in the lower portion of the slot C' at the rear of the firing-pin when the spring has been compressed. The lug e' projects from the sear downward through a slot, b', in the breech-block.

G G are arms having projections at right angles with them at the front end, through which a pin passes to pivot them to the rear portion of the barrel and out of line with the hinge-pin of the breech-block, as shown at G'. 95 The rear of the arms G have slots made in them, and the transverse bar C has its ends projecting far enough to enter the slots in the bars G. When the breech-block is opened, moving about its pivot-pin in front, the arms 100 G are turned up along with it, and as they have the center about which they move out of line with the center of motion of the breech-block B it will be seen that the slot g at the

ends of the arms will act upon the projecting arm c' and press it backward, thus withdrawing the firing-pin and compressing the spring D against sear E. This action causes the sear-noses e to engage notches c in the firing-pin, and thus hold the firing-pin back while the breech-block is being closed. The cartridges are contained in a segment of a cylinder, I, which extends around beneath the receiver A, within which the breech-block closes, and this holder is of a length sufficient to receive the cartridge, and the distance between its inner and outer sides is sufficient for the diameter of the cartridge.

15 The cartridge-follower i is acted upon by springs or other mechanical contrivances, so as to cause it to press the cartridges sidewise and force them to travel around in the annular chamber which the casing I forms beneath the receiver A. i' is a hinged lid or door at the left side of the cartridge case or holder. This side extends up high enough to allow the lid to swing inward above the receiver A when the breech-block B has been thrown open. While the breech-block is open the lid i may be operated by the thumb of the right hand, or by a fixed spring, and the cartridge will be dropped into the receiver, when it can be pushed in the chamber of the gun by forward movement of the thumb. When the breech-block is closed, it acts to close the lid i of the cartridge case or receiver, and allows another cartridge to be brought into position ready to drop into the receiver A when the breech-block is again opened. When the breech-block is closed, the cam-latch h' falls into the cavity provided for it at the rear of the receiver A, and the thumb-piece h may be pressed laterally, so as to engage with the safety-notch H, to prevent the breech-block flying open, as before described.

F is the trigger of the gun. F' is a bar or link extending from this trigger forward, having its front end attached to the lower end of the ejector-stud f , which is pivoted below the receiver A, and its point extending upward, as shown. When the trigger is pulled, it acts through the rod F' and the ejector-stud f , causing it to oscillate upon its pivot, so that the upper part of the stud moves backward and acts upon the lug e' of the sear E, and this disengages the ends e of the sear from the notch c , and allows the firing-pin C to be forced forward by the mainspring D, so that its point

C will strike and explode the cartridge. If it is desired, the magazine may be detached and the gun will operate as a single breech-loader.

Having thus described my invention, what I claim as new, and desire to secure by Letters Patent, is—

1. In a gun, the receiver A, hinged swinging breech-block B, with arms pivoted upon each side and eccentrically to the pivot of the breech-block, together with the firing-pin sliding within the breech-block containing a mainspring, and having a transverse bar, c' , the ends of which engage slots in the arms G, so that the firing-pin may be retracted and the spring compressed by the opening of the breech-block, as herein described. 70

2. In a gun, the receiver A, hinged swinging breech-block B, the tubular firing-pin contained within the breech-block, and itself containing the mainspring, with a means for retracting the firing-pin and compressing the mainspring, together with the sear E, pivoted below its center, and having sear-noses e , adapted to engage notches c in the slotted rear end of the firing-pin, as herein described. 75

3. In a gun, the receiver A, hinged swinging breech-block B, with its contained hollow firing-pin, and mainspring contained within the breech-block, and the sear E, pivoted and having noses or catches, as shown, together with the ejector-stud f , connected with the trigger F, substantially as herein described. 80

4. The receiver A, swinging breech-block, with the arms G turning upon different centers, the contained firing-pin, mainspring, and holding mechanism within the breech-block, in combination with the cam-latch located within the rear end of the breech-block, to hold the same within the receiver, a thumb-piece, h , and safety-notch H, substantially as described. 90

5. In a gun, the receiver A, hinged swinging breech-block B, with its contained firing-pin, spring, and actuating mechanism within the breech-block, and the arms G, in combination with the segmental magazine I, extending beneath the receiver, and the lid i' , substantially as herein described. 95

In witness whereof I have hereunto set my hand.

JOHN C. KELTON.
